DESIGN FOR A VACUUM CLEANER CASING

Clarence Karstadt, Glen Ellyn, Ill.

Application October 4, 1945, Serial No. 122,531

Term of patent 14 years

(Cl. D9—2)

To all whom it may concern:

Be it known that I, Clarence Karstadt, a citizen of the United States, residing at Glen Ellyn, in the county of Du Page and State of Illinois, have invented a new, original, and ornamental Design for a Vacuum Cleaner Casing, of which the following is a specification, reference being had to the accompanying drawings, forming a part thereof, in which:

Fig. 1 is a plan view of a vacuum cleaner casing showing my new design; Fig. 2 is a side elevation thereof; Fig. 3 is a front elevation; and Fig. 4 is a rear elevation.

I claim:

The ornamental design for a vacuum cleaner casing, substantially as shown.

CLARENCE KARSTADT.
